UNITED STATES PATENT OFFICE.

ARTHUR LAUZON, OF BIDDEFORD, MAINE, ASSIGNOR TO CROMPTON & KNOWLES LOOM WORKS, OF WORCESTER, MASSACHUSETTS, A CORPORATION OF MASSACHUSETTS.

WEFT-REPLENISHING MECHANISM.

1,261,563.

Specification of Letters Patent.

Patented Apr. 2, 1918.

Application filed July 23, 1917. Serial No. 182,244.

To all whom it may concern:

Be it known that I, ARTHUR LAUZON, a citizen of the United States, residing at Biddeford, in the county of York and State 5 of Maine, have invented a new and useful Weft-Replenishing Mechanism, of which the following is a specification.

This invention relates to weft replenishing mechanism and particularly to improved devices for supporting a weft carrier in position for transfer and for thereafter releasing said weft carrier on failure of transfer.

Such devices have been heretofore used 15 but have been commonly of a type in which the support is actuated on every alternate beat of the lay. Such actuation is objectionable as the operation is entirely without useful function except after the indication 20 of a transfer. The parts are thus subject to much needless wear with no corresponding advantages.

It is the object of my present invention 25 to provide a weft carrier support which remains in inoperative position until a transfer is indicated and returns to inoperative position immediately after its function has been performed.

In the embodiment of my invention here- 30 disclosed the weft carrier support is associated with the shuttle feeler and is moved to operative and inoperative positions substantially simultaneously with said feeler.

With this general object in view, my invention relates to certain arrangements and combinations of parts hereinafter disclosed and more particularly pointed out in the appended claims.

A preferred form of my invention is 40 shown in the drawings, in which

Figure 1 is a right-hand side elevation of one end of a weft replenishing magazine with my improved weft carrier support embodied therein;

Fig. 2 is a detail side elevation showing certain of the parts of Fig. 1 in a different position, and

Fig. 3 is a sectional plan view taken 50 along the line 3—3 in Fig. 2.

Referring to the drawings, I have shown a portion of an end frame 10 of a two-color magazine of the stationary type. The magazine is provided with guide ways 11 and 12

for weft carriers of different colors, and 55 suitable mechanism (not shown) is provided for releasing a weft carrier of the desired color upon the indication of transfer, said carrier then moving to the position of the carrier W in Fig. 1. A transerrer 13 of 60 the usual type is provided for thereafter transferring the weft carrier W to the exhausted shuttle. All of the parts thus far described may be of the usual type and form no part of my invention. 65

It is necessary to support the weft carrier in the position indicated at W in Fig. 1 until the descent of the transerrer 13 by which the weft carrier is forced into the exhausted shuttle. It sometimes happens, 70 however, that the shuttle will be misplaced in the shuttle box to an extent which renders a successful transfer impossible. In this event the transfer is revoked and it is necessary that the weft carrier W be re- 75 leased and removed so that the magazine will be in condition to perform the next indicated transfer, which may be of a different color.

For thus alternately holding and releasing the weft carrier W I provide a support 14 pivoted upon a stud 15 secured in the frame 10. A spring 16 encircles the stud 15 and is attached at one end to the hub of the support 14 and at the opposite end 85 to a collar 17 angularly adjustable on the stud 15. The spring 16 acts to force the support 14 yieldingly into operative position.

The support 14 is provided with a rearwardly extending arm 18 overlying a stud 19 on an arm 20 secured to a rock shaft 21. The shaft 21 is rotatable in fixed bearings in the frame 10 and has secured thereto a shuttle feeler 22 and an arm 23 connected by a link 24 to control mechanism not shown. Said control mechanism is, however, fully shown and described in the prior patent to Ryon No. 972,722, issued October 11, 1910, and it need be stated merely that the link 24 is secured to an arm mounted upon a shaft corresponding to the shaft 38 of the Ryon patent, the parts being so connected that the link 24 will be raised to the position shown in Fig. 2, when the parts of the control mechanism are in the inoperative position shown in Fig. 7 of the patent. Furthermore, the parts are yieldingly retained 100

in this position by the action of the toggle members 39 and 42 and the toggle spring 44 of the patent.

In this position also the shuttle feeler 22 is raised out of the path of the box plate 25 carried by the lay 26. When a transfer is indicated the link 24 is depressed, thus moving the feeler 22 to operative position as shown in Fig. 1, and also permitting the spring 16 (Fig. 3) to move the weft carrier support 14 to its operative position, also shown in Fig. 1. The weft carrier then moves to the position indicated at W and is normally transferred immediately thereafter to the exhausted shuttle.

As the lay 26 completes its forward stroke the box plate 25 engages the shuttle feeler 22, returning the same to the inoperative position shown in Fig. 2, in which position it is yieldingly retained by the control mechanism above described. As the shuttle feeler moves upward the stud 19 on the arm 20 is also moved upward, thus raising the rearward extension 18 of the support 14 and depressing the operative portion of the support, which moves to the inoperative position shown in Fig. 2 and releases the weft carrier W if said carrier still remains in the magazine.

The parts are thus restored to their original inoperative position in which they remain until a transfer is again indicated and the link 24 is again actuated to depress the feeler 22 and permit upward movement of the support 14 to operative position. The parts thus remain at rest during the entire operation of the loom except for the occasional periods of transfer.

Having thus described my invention, it will be evident that changes and modifications can be made therein by those skilled in the art without departing from the spirit and scope of my invention as set forth in the claims, and I do not wish to be limited

to the details herein disclosed, but what I claim is—

1. In a loom, a magazine, a weft carrier support maintained in inoperative position during the normal operation of the loom, means to move said support to operative position, when a weft carrier transfer is indicated, and means to thereafter return said support to inoperative position.

2. In a loom, a magazine, a weft carrier support maintained in inoperative position during the normal operation of the loom and rendered effective after a transfer indication to hold a weft carrier in said magazine in transfer position, and means to withdraw said support to release a weft carrier which fails of transfer.

3. In a loom, a magazine, a weft carrier support maintained in inoperative position during the normal operation of the loom, yielding means effective to move said support to operative position upon indication of transfer, and means to positively withdraw said support from operative position after the completion of the transfer operation.

4. In a loom, a magazine, a normally inoperative weft carrier support, a normally inoperative shuttle feeler, means to give said feeler and said support substantially simultaneous movements to operative position upon an indication of transfer, and connections between said feeler and said support whereby said feeler is effective to return said support to inoperative position.

5. In a loom, a magazine, a normally inoperative weft carrier support, a shuttle feeler, and connections between said feeler and said support whereby movement of said feeler to operative position permits said support to move to operative position.

In testimony whereof I have hereunto affixed my signature.

ARTHUR LAUZON.
